UNITED STATES PATENT OFFICE.

FREDERICK KOHNLE, OF DAYTON, OHIO.

PIN-TICKETING MACHINE.

1,028,225.

Specification of Letters Patent.

Patented June 4, 1912.

Application filed December 13, 1909. Serial No. 532,874.

To all whom it may concern:

Be it known that I, FREDERICK KOHNLE, a citizen of the United States, residing at Dayton, in the county of Montgomery and 5 State of Ohio, have invented certain new and useful Improvements in Pin-Ticketing Machines, of which the following is a specification.

My invention relates to an improvement 10 in a pin ticketing machine of the type shown and described in my applications filed on April 30, 1906, Serial No. 314,456, and filed on April 29, 1907, Serial No. 370,990.

The present invention relates to various 15 detail improvements in certain of the mechanisms included in such machine, said improvements all tending or coacting to simplify the construction and generally produce a more efficient operation.

20 One of the objects of my invention is to provide a continuous strip of paper with perforations at intervals and positive actuated feeding means, adapted to engage into said perforations for feeding the strip in step movements.

Another object of my invention is to provide a pin-ticketing machine capable of making straight staples, inserting them through a tag or clenching them upon the 30 material desired to be ticketed, with means whereby the clenching actuating mechanism is automatically thrown out of commission when the straight staple mechanism is thrown into commission.

35 Another object of my invention is to provide an intermittently actuated ink ribbon of endless form, actuated upon the reciprocation of the main actuating mechanism.

The various other features of my invention 40 are more fully set forth in the description of the accompanying drawings, forming a part of this specification, in which:—

Figure 1 is a side elevation of my improved pin ticketing machine, illustrating 45 the tag stapling arm partly swung out of use and with the cover plate broken away to expose the inking mechanism. Fig. 2 is a section on line x , Fig. 1. Fig. 3 is a front elevation of the machine. Fig. 4 is a section 50 on line y , Fig. 3. Fig. 5 is a vertical section on line w , Fig. 3, through the supporting platen with the tag feeding mechanism shown in elevation and with the staple forming mechanism omitted. Fig. 6 is a 55 plan view of the strip of paper provided with a series of perforations equally spaced.

In my present invention the frame with its main actuating slide plate, staple former and driver, ratchet mechanism for preventing reverse movement of the slide plate during a partial stroke thereof, clenching mechanism, wire feed and cutting mechanism and tag cutting mechanism, and type chase are all substantially the same as that illustrated and described in the foregoing applications, and, therefore, will not herein give a detailed description of such mechanism.

This invention relates to the same type of machine for making and attaching tickets 70 to textile fabrics in which a paper card or the like is fed beneath the printing mechanism and printed with any desired data, a portion being thereupon detached to form a ticket, which is fed out of the machine after 75 being pierced by a wire staple formed by mechanism contained in the machine, the staple being either clenched or attached to the fabric brought to the machine, or, remaining straight and fed from the machine, 80 according to requirements.

In the drawings, the head of the pin-ticketing machine is only illustrated, but which in practice is mounted upon a pedestal base constructed preferably of hollow 85 form, with a treadle pivoted thereto and a connecting rod projected upward in connection with the treadle at one end and to the main actuating slide plate at the opposite end for the down stroke of the slide 90 plate, and a spring for returning the same automatically to normal position when a manually operated pin ticketing machine is desired. It is obvious, however, that the main slide plate may be reciprocated in any 95 well-known manner, either manually operated or by power means.

1 represents the base plate of the head, 2 the main frame secured to the base plate, said frame is provided with a slide-way 100 supporting the slide plate 3 and within which the same is reciprocated.

4 represents the connecting rod connected to the slide plate for actuating the same. Ratchet mechanism is provided upon the 105 rear of the frame and slide plate for insuring a full stroke of the slide plate and all co-operating parts in both directions of movement, fully described as to the details of construction in said aforementioned applications. This mechanism includes a ratchet plate provided with oppositely directed 110

teeth at the front and back and resiliently mounted on the main frame 2, and a second similar ratchet plate on the slide plate co-acting with the frame ratchet plate. On 5 the movement of the slide plate in one direction, the ratchet thereon slides behind the ratchet on the frame until the ratchets have cleared one another; in such movement the front teeth of the slide plate ratchet 10 interlock with the head ratchet. When, however, the full stroke has been completed and the return movement taken place, the slide plate ratchet moves in front of the frame ratchet, owing to the inclined formation upon the ends of the ratchet when 15 the reverse operation takes place.

5 represents the staple former and driver mechanism, which also in details of construction, is substantially the same as that 20 shown and described in my said former applications, in which the staple driver is actuated within a staple bender or sleeve formation, the bender having yoke limbs passing over an anvil with connections between 25 the slide plate and stapling mechanism and cam mechanism for operating the various parts, their proper proportional distances upon the movement of the slide plate.

6 represents the paper cutting mechanism 30 mounted beneath the stapling mechanism and actuated by rods 7 in connection with the stapling mechanism, so as to actuate the cutter mechanism upon the downward movement of the slide plate.

35 7^a represents the wire feeding mechanism, the details of construction and operation being substantially the same as that described in said former applications, in which the wire passes between a pair of rollers maintained under frictional contact with each 40 other, and pawl and ratchet mechanism in connection with the slide plate and wire feeding rollers for imparting a predetermined feed movement to the wire upon each 45 up stroke of the slide.

8 represents a wire severing blade, see Fig. 3, which in details of construction and mode of operation is substantially the same as my former application, filed April 29, 50 1907, Serial No. 370,990, in which the knife is actuated against a stationary cutter block, by means of a bell crank lever and connections with the main slide plate, whereby the wire is severed and the return movement of 55 the blade is effected during the downward movement of the main slide plate.

From the foregoing description and reference to the separate applications heretofore mentioned, the operation of the machines together with the hereinafter described features, can be readily understood.

The clenching of the staple is accomplished by mechanism substantially the same as that shown in my former application, 65 Serial No. 370,990, filed April 29, 1907, in

which, 9 represents a support mounted on the base plate 1, provided with vertically extended rods 10, to which are slidably mounted the ears 11, formed integral with the clenching block frame 12, forming guiding instrumentalities therefor. The frame 12 is slotted, through which the lifting lever 13 projects, said lever being pivotally supported at 14 upon an ear projecting from the support 9. 75

15 represents a link arm pivotally secured upon the stud 16, which in turn is secured to the slide plate 3, and maintained under spring tension to move in a direction toward the lifting lever 13, and limited in movement by engaging a pin 17, projected from the slide plate 3, said link arm and lever are notched and adapted to engage with each other, as shown in Fig. 1, whereby when the slide plate 3 moves down the rear end of the lever 13 is depressed, raising the forward end for actuating the clenching block frame 12. 80

18 represents a pawl pivotally secured upon the frame 9, provided upon its inner face with a notch, as shown in dotted lines, Fig. 1, said notch being provided with an angular surface 19, against which the pin 20, fixed to the link arm 15, engages, to release the link arm from engagement with the lever 13. This allows the lever 13 to be forced back to normal position prior to a complete movement of the slide plate by the weight of the clenching block frame. 90

21 represents a slotted rod through which the lever 13 projects, sliding vertically in a bore formed in the clenching block frame 12. 22 represents a coil spring encircling said rod, one end of which bears against the collar 23, loose upon said rod, while its opposite end engages against the collar 24 fixed to the free end of said rod. This construction forms a yielding support for the clenching block. The fabrics to be ticketed, varying in thickness, and with the clenching block yielding, serves to automatically adjust the same relatively to the stapling mechanism. 100

25 represents the clenching block fixed to the upper surface of the clenching block frame and provided with clenching grooves. 105

26 represents a guard formed over the outer edge of the grooves to prevent the staple limbs or points from being forced into the goods. If, however, it is desired 110 to form stapled tags to be afterward applied upon the goods or otherwise, I provide the following instrumentalities:—27 represents an arm hinged to the frame 2, see Figs. 3 and 4, adapted to be swung beneath the stapling mechanism. This arm is provided with the slots 28, through which the limbs of the staple pass, the tag resting upon the top surface of the arm 27, and in operation the staple is formed by the 115 120 125 130

staple bender after the wire is severed by the cutter and bent over the anvil, the anvil moved out of position and the limbs of the staple moved downward by the staple driver 5 through the tag and notches 28. Such stapling operation necessarily requires that the clenching mechanism be thrown out of commission, and this is accomplished as follows:—29 represents a catch-pin fixed to 10 the arm 27, adapted to engage with the lever 30, pivoted to the frame 2 at one side of the tag platen, see Fig. 1, which engagement will swing the free end of said lever 30 upward, engaging the pin 20 of the link 15 arm 15, throwing the same out of possible engagement with the lever 13, during the downward movement of the slide plate 3. By this construction, the two stapling operations can be readily thrown into or out 20 of commission with safety, for the tag straight stapling mechanism cannot be thrown into commission without throwing out the clenching mechanism, and the reverse follows as soon as the arm 27 is swung away 25 from beneath the staple forming mechanism.

It is generally desirable to use a pre-printed tag in machines of this class, with the printing mechanism merely employed 30 for inserting or printing changeable data, such as number marks and price marks. The preprinted tags are in the form of a continuous strip which require positive feeding to properly align each tag with the 35 printing, cutting and stapling mechanism, for the reason that any slight slippage of the strip in such feeding would throw out the alignment. This positive feeding of the continuous strip of paper, is accomplished 40 by providing a series of preferably equally spaced perforations, located for example at the center thereof, as illustrated in Fig. 6. The strip of paper is wound in the form of a roll mounted in a storage reel, preferably 45 at the rear end of the machine, not shown in the drawings. From this storage reel the strip is passed over the platen 31, between a guide 32 at one end thereof, see Figs 1 and 5, from whence it is fed beneath 50 the printing, tag-cutting and staple forming mechanism. 33 represents a bell crank lever pivoted at 34 to the frame 2, with the arm 35 provided with a yoke end, with the limbs 36 adapted to engage with a pin 37, 55 fixed and projected from the slide plate 3, to actuate said lever 33 in proper time movements and in a sufficient arc during the reciprocation of said slide plate to properly feed the strip of paper 38. 39 represents a 60 resilient feed finger pivotally mounted to the second arm of the bell crank lever 33 and extended horizontally over the strip of paper. This feed finger is provided with a point or nose 40, adapted to engage successive perforations 41 in the strip, to feed

the same to the discharge or exit portion of the machine. The point 40 of the finger 39 during its feeding action engages into a groove 42, formed on the top face of the platen 31, to prevent lateral displacement of 70 the finger in its feeding action.

Owing to the resiliency of the finger 39 in the reverse movement of the bell crank lever 33, the point will readily withdraw from its engaged perforation without disturbing the strip of paper and travel loosely over the paper to be engaged into a successive perforation for a second operation. The yoke formation of the arm 35 of the bell crank lever 33 is provided to impart a 75 proper time movement upon the reciprocation of the slide plate 3.

It is very desirable in machines of this class to make a proper printing impression upon the tag strips, and in which it is sometimes desirable to print in several colors, and this is accomplished by employing an endless ribbon 44, passing over a series of guide rollers 45, journaled in a casing 46, mounted upon the frame 2, with a portion 80 of the ribbon continuously fed beneath the type chase 47, detachably mounted upon the reciprocating slide plate 3. This type chase and its mounting are substantially the same as that shown and described in said former 85 applications.

48 represents a feed roller suitably journaled within the casing 46, over which the ribbon passes, and 49 represents a tension roller carried by the pivotally mounted arm 100 50, said roller maintaining the proper tension to the endless ribbon, upon the periphery of the feed roll 48. The feed roll is preferably rotated in step movements by the following instrumentalities, (see Figs. 2 and 105 5) :—51 represents a spring controlled pawl pivotally mounted upon the slide plate 3, and held against movement in one direction by a pin 52, projecting from the slide plate 3. 53 represents a tooth, see Fig. 5, projecting from the pawl, adapted to engage with the teeth of the ratchet wheel 54, fixed to the feed roll 48. Upon the downward movement of the slide plate, the pawl tooth will engage with the ratchet wheel and be 110 58 swung away from the pin 52, in an upward direction, until the slide plate has moved downwardly sufficient to permit the pawl tooth to pass the periphery of the ratchet wheel when it will snap into its normal position, and in the path of tooth engagement with the ratchet wheel upon upward travel of the slide plate 3, thereby moving or rotating the ratchet wheel feed roller and ribbon one step. This construction provides a 115 continuous feed of the ribbon, presenting a new surface beneath the type after each printing operation, lengthening the life of the ribbon and a uniform impression upon the tag. The ribbon is readily removable 120 125 130

by swinging the tension roller 49 upwardly and in providing the ribbon with two or more colors, common in the manufacture of ribbons, color printing can be had.

5 Having described my invention, I claim:—

1. In a machine of the class described, a frame, a reciprocating member mounted thereon, staple forming mechanism actuated by said reciprocating member, staple clenching mechanism, a lifting lever engaging the same, a spring controlled arm pivotally mounted on said reciprocating member adapted to engage said lifting lever, ticket stapling mechanism movable into and out 10 of operative position with said forming mechanism, and means controlled thereby for disengaging said arm from the lifting lever when said ticket stapling mechanism is in commission, said disconnected members 15 automatically engaging when the ticket stapling mechanism is out of commission.
2. In a machine of the class described, a frame, a reciprocating member mounted thereon, staple forming mechanism actuated 20 in proper time movement by said reciprocating member, staple clenching mechanism in operative connection with said reciprocating member and operated in proper time movements relative to the staple forming 25 mechanism, and ticket stapling mechanism adapted to be thrown into operative posi- 30

tion with said stapling mechanism, and means under the control of said ticket stapling mechanism for disengaging the operative connection between reciprocating member and clenching mechanism when the ticket stapling mechanism is in commission. 35

3. In a machine of the class described, a frame, a reciprocating member mounted thereon, staple forming mechanism actuated by said reciprocating member, staple clenching mechanism in operative connection with said reciprocating member, ticket stapling mechanism mounted on said frame, adapted to be moved into operative position with 40 said staple forming mechanism, and means for disengaging the operative connection between said reciprocating member and staple clenching mechanism when moving said ticket stapling mechanism into commission, 45 and automatically connecting said operative connections between said reciprocating member and staple clenching mechanism, when throwing said ticket staple clenching mechanism out of commission. 50

55 In testimony whereof, I have hereunto set my hand.

FREDERICK KOHNLE.
